UNITED STATES PATENT OFFICE.

CHARLEY MONROE STUDEBAKER, OF CENTROPOLIS, KANSAS, ASSIGNOR OF ONE-HALF TO GEORGE WASHINGTON STUDEBAKER AND ONE-HALF TO JOHN L. TURNER, BOTH OF CENTROPOLIS, KANSAS.

GAS-HEATER FOR AUTOMOBILES.

1,321,680.

Specification of Letters Patent. Patented Nov. 11, 1919.

Application filed January 17, 1919. Serial No. 271,657.

To all whom it may concern:

Be it known that I, CHARLEY MONROE STUDEBAKER, a citizen of the United States, and a resident of Centropolis, county of Franklin, and State of Kansas, have invented certain new and useful Improvements in Gas-Heaters for Automobiles, of which the following is a specification.

My present invention relates generally to gas heaters, and more particularly to an attachment for automobiles to assist in starting in cold weather, my object being the provision of a simple, inexpensive arrangement which may be quickly applied, and which may be utilized without inconvenience and will effectively and efficiently operate for the intended purposes.

More particularly my invention relates to that type of heater in which a casing is secured to surround a portion of the intake manifold of a combustion engine, having provision for the ready introduction of combustible matter as well as provision for the introduction of the heat units and products of combustion thereof into the air intake pipe of the carburetor, so as to actually introduce preheated gases within the combustible mixture for the motor as well as heat the intake manifold through which the combustible mixture passes from the carburetor to the motor.

In the accompanying drawings illustrating my invention and forming a part of this specification:

Figure 1 is a perspective view illustrating the practical application of my invention;

Fig. 2 is a similar view on a slightly enlarged scale, with the cover of the heater casing removed and in detached relation;

Fig. 3 is a detail perspective view of the pad holder;

Fig. 4 is a vertical section through the air intake pipe and taken substantially on line 4-4 of Fig. 1.

Referring now to these figures, my invention resides in the provision of a casing generally indicated at 10, in connection with the intake manifold 11 of an internal combustion motor, this casing having its base 12 apertured to receive the vertically extending portion of the manifold and provided with side walls 13 inclined upwardly and outwardly from the sides of the base 12 with their upper ends concavely recessed at 14 to

receive the lateral portions of the manifold. 55 A back plate 15 is connected to the rear edges of the sides 13 and has its upper portion 16 curved to partially surround the manifold so as to coöperate with the upper curved portion 17 of the front wall or cover 60 18, the upper curved portion 17 of which partially surrounds the opposite side of the manifold as clearly seen in Fig. 1. This front wall or cover plate engages the front edges of the base 12 and sides 13 and is secured in its operative position to the casing by means of bolts and nuts 19 as seen in Fig. 1.

One side wall 13 has an opening communicating with the upper end of a depending box-like extension 20 of the casing, the upper end of which is secured to the casing around the said opening of its side wall, and one side of which has an opening 21 normally closed by a hinged cover 22. This 75 extension 20 of the casing also has a hinged base plate 23 normally closing its lower open end and provided with a central draft opening 24.

Within the casing 10 a woven wire or 80 other holder 25 surrounds the vertical portion of the manifold 11 and provides for the reception and support of a pad or pads 26 to which a combustible material such as gasoline may be supplied through the box-like extension 20 of the casing with the side door or cover in the open position shown in Fig. 1, so that upon igniting said combustible material the heat of its combustion will be transmitted directly to the intake 90 manifold with which it is in contact.

At the same time the casing cover 18 has an opening communicating with one end of a heating pipe 27, which is preferably of a flexible nature, having a valve 28 therein 95 at a convenient point in its length and having its opposite end secured to surround an opening in the air intake pipe 29 of the carburetor 30, which carburetor also connects with the intake manifold as usual. In thus 100 connecting the pipe 27 with the air intake pipe, the respective end of the pipe 27 has an annular series of longitudinal slits forming tongues 31 as seen in Fig. 4, certain of which, for instance alternate tongues, are 105 bent outwardly to bear upon the external surface of pipe 29, and the others of which are permitted to extend inwardly of the

opening of the pipe. A clamp 32 surrounding the pipe 29 and with portions thereof overlying the outwardly bent tongues of the pipe 27 thus securely fastens the two pipes together.

In operation, when it is desired to start the motor in a cold state, the combustible fluid is introduced as above described and as illustrated in Fig. 1, and the intake manifold 10 comes promptly warmed so as to preheat the combustible mixture on its way to the cylinders of the motor and thus permit of easy starting. At the same time the valve 28 of the pipe 27 is opened and the carburetor 15 thus sucks along with air through pipe 29, a portion of the heat products from within the casing 10 as well as gases of combustion, thus commingling with and heating the air supply so as to bring about the passage of 20 heated air through the carburetor to more effectively take up and join with the combustible fluid.

It is obvious that my invention provides a device of this nature which may be quickly 25 installed, and which may be utilized conveniently and effectively, and which will be durable in operation.

I claim:

1. The combination with the carburetor, 30 and the air pipe and intake manifold to which the carburetor is connected, of a casing secured to surround a portion of the intake manifold, having pad holding means therein and provided with a hinged door, 35 and a pipe connected at one end to the said casing and at its opposite end to the said air pipe of the carburetor and having a valve, for the purpose described.

2. The combination with the intake manifold, carburetor, and carburetor air pipe of 40 a motor, said air pipe having an opening adjacent the carburetor, of a pipe one end of which is clamped to the said air pipe to register with the opening thereof, a valve 45 within the last mentioned pipe, and a heater

surmounting a portion of the intake manifold, and to which the opposite end of the last mentioned pipe has a communicating connection.

3. The combination with the intake manifold of a motor, of a casing having an apertured base to receive through its aperture one leg of the manifold and provided with side walls, the upper ends of which are concavely recessed to receive the other leg of 50 the manifold, said casing including a rear wall the upper end of which is curved to partially surround the intake manifold at one side, a cover plate secured to normally cover the opposite side of the casing and 55 having its upper portion curved to partially surround the opposite side of the manifold, said casing having an extension at one side opening into the same and provided with a normally closed door to permit of ready access to the interior of the casing for the purpose described.

4. The combination with the intake manifold of a carburetor and a carburetor air pipe of a motor, said air pipe having an 60 opening therein adjacent to the carburetor, of a pipe having a valve and provided with an annular series of longitudinal slits at one 65 end forming an annular series of tongues certain of which are extended into the air pipe 70 opening and certain of which are bent outwardly to engage the external surface of the air pipe, a clamp surrounding the air pipe and having portions thereof overlying the outwardly bent tongues to secure the last 75 mentioned plate upon the air pipe, and a heater surmounting a portion of the intake manifold and with which the opposite end of the last mentioned pipe communicates for the purpose described.

CHARLEY MONROE STUDEBAKER.
